A. F. FARMAN

SPARK PLUG

Filed Jan. 2, 1923

WITNESS

J. R. Gardner

INVENTOR
A. F. FARMAN

BY

Joseph B. Gardner
his ATTORNEY

UNITED STATES PATENT OFFICE.

ARTHUR F. FARMAN, OF OAKLAND, CALIFORNIA.

SPARK PLUG.

Application filed January 2, 1923. Serial No. 610,182.

To all whom it may concern:

Be it known that I, ARTHUR F. FARMAN, a citizen of the United States, and a resident of Oakland, county of Alameda, and State of California, have invented a new and useful Spark Plug, of which the following is a specification.

My invention relates to spark plugs and particularly to means for pre-heating the same.

An object of the invention is to provide a spark plug with means which will facilitate the starting of the engine associated therewith.

Another object of the invention is to provide simple means for electrically heating the plug and which may be arranged directly within and readily incorporated with practically any of the ordinary types of spark plug.

The invention possesses other objects and features of advantage, some of which, with the foregoing, will be set forth in the following description of the preferred form of my invention which is illustrated in the drawing accompanying and forming part of the specification. It is to be understood that I do not limit myself to the showing made by the said drawing and description, as I may adopt variations of the preferred form within the scope of my invention as set forth in the claim.

Referring to said drawing:

The figure is a partly sectional view of a spark plug provided with one form of the heating means of my invention.

The difficulties attending the task of starting an internal combustion engine when the surrounding temperature is comparatively low are well known, and as heretofore stated it is one of the chief aims of the present invention to eliminate this annoying feature. I have found that by heating the explosive mixture within the spark plug or adjacent thereto or both, prior to attempting to explode said mixture, that practically no difficulty is encountered in starting engines of large size and under extremely unfavorable conditions as to temperature. In accordance with the foregoing I have therefore incorporated with the ordinary spark plug suitable means for pre-heating the explosive mixture adjacent the ignition arc.

Briefly expressed the structure as here shown comprises the usual bushing provided with one of the electrodes and in which is arranged the insulating core containing the central electrode. The heating element consists of a coil which encircles the insulating core, is grounded at one extremity, and is connected at its other extremity to a source of electrical energy by means of a novel connection insulated from but supported by the bushing.

A detailed description follows:

The invention in its present embodiment is shown in connection with an ordinary spark plug 2 having a bushing 3 suitably threaded for enabling it to be screwed into the cylinder head of an internal combustion engine, and provided at its lower extremity with the usual electrode 4. The core 6, generally formed of porcelain or similar insulating material, is removably arranged within the bushing and is provided with the electrode 7 centrally disposed therein. The plug is also provided with the usual gland 8 and packing rings 9 which engage the core adjacent the shoulder 12.

Preferably arranged on the core 6 is a heating element 13 which as here shown is in the form of a coil 14 encircling the core and adapted to be heated to a comparatively high temperature by having a current of electricity passed through it. On end 16 of the coil is preferably grounded by connecting it to one of the metallic packing rings 9, whereas the other end 17 is attached to a metallic collar 18 in contact with a spring element 19 formed on the inner extremity of the post 21, the connection between the collar and post thus insuring the proper electrical contact and at the same time permitting of the unhampered withdrawal or insertion of the core. The post 21 is suitably insulated from and supported by the bushing 3, and is connected by a lead 22 to a convenient source of electric current such as a battery 23. The lead 22 is provided with a switch 24 for opening or closing the circuit.

It will now be understood that with the use of my invention, by throwing the switch to heat the coil for a comparatively short space of time, the engine will ordinarily start without any difficulty.

I claim:

A spark plug comprising a bushing, an insulating core removably positioned therein, an electric heating element arranged on the outer side said core and having one terminal electrically connected to said bushing, a conductor electrically connected to the other terminal of said element and encircling said core on its exterior, and a resilient con-

tact mounted on and insulated from said bushing and arranged to engage said conductor.

In testimony whereof, I have hereunto set my hand at Oakland, this 15th day of December, 1922.

ARTHUR F. FARMAN.
